UNITED STATES PATENT OFFICE.

OTTO M. GILBERTSON, OF LA CROSSE, WISCONSIN.

RAILWAY-MAIL-DELIVERING APPARATUS.

1,353,738.

Specification of Letters Patent. Patented Sept. 21, 1920.

Application filed June 12, 1919. Serial No. 303,536.

To all whom it may concern:

Be it known that I, OTTO M. GILBERTSON, a citizen of the United States, residing at La Crosse, in the county of La Crosse and 5 State of Wisconsin, have invented certain new and useful Improvements in Railway-Mail-Delivering Apparatus; and I do declare the following to be a full, clear, and exact description of the invention, such as 10 will enable others skilled in the art to which it appertains to make and use the same.

My invention has for its principal object to provide a comparatively simple, yet a highly efficient and reliable means for delivering mail bags from moving trains, without the danger of injury either to the bag or its contents, and in carrying out this 15 object, other objects are to provide a traveling car to receive the sack; to provide for slowly checking the movement of the car after the sack is deposited therein; and to devise an arrangement whereby the entire 20 apparatus may be employed regardless of the direction in which the train is traveling.

25 With the foregoing in view, the invention resides in the novel construction and arrangement of parts hereinafter described and claimed, the descriptive matter being supplemented by the accompanying drawings forming a part of this application.

Figure 1 is a perspective view of the invention showing the same in readiness to deliver a sack of mail.

Fig. 2 is a transverse section through one 35 of the mail cars and the tracks of the receiving car, showing an elevation of the different parts carried by said car and tracks.

Fig. 3 is a horizontal section on the plane of line 3—3 of Fig. 2.

40 Fig. 4 is a vertical section on the plane of line 4—4 of Fig. 3.

Figs. 5 and 6 are detail vertical sections through the sliding arm and its guide, as seen on the plane of lines 5—5 and 6—6 of 45 Fig. 2.

Fig. 7 is an end elevation of the car carried arm and the bag holding means thereon.

Fig. 8 is a view similar to Fig. 7 but illustrating the reversible head of the holding means in section.

Fig. 9 is a horizontal section on the plane of line 9—9 of Fig. 7.

Fig. 10 is a disassembled perspective of 55 the car carried arm and its reversible head.

Fig. 11 is a longitudinal section of the bag receiving car and associated parts.

Figs. 12 and 13 are transverse sections on the planes indicated by the lines 12—12 and 13—13 of Fig. 11.

The present disclosure includes a fixed unit F disposed at one side of the railway track, and a traveling unit T mounted on a mail car of a train, and both units are constructed in a novel manner. The traveling 65 unit however forms the subject matter of another application.

The unit F includes a mail bag receiving car 1 having wheels 2 traveling on tracks 3, and a shock absorber 4 to gradually bring 70 said car to a standstill after the mail has been deposited therein. The car 1 is open at its top and at one end, while its opposite end is closed and is provided with a bumper 5 which is preferably hinged as seen at 6 in 75 Fig. 11, and provided with a shock absorbing spring 7. A sack strikes the bumper 5 when it is received in the car 1, and the shock is thus greatly absorbed, such shock, however, serving to start the car 1 along its 80 tracks 3, against the checking action of the shock absorber 4.

The tracks 3 may well be located on a longitudinally extending horizontal frame 8 centrally pivoted at 9 for swinging horizontally to position the car 1 for receiving mail from trains approaching in either direction. Suitable supports 10 may be provided for the ends of the frame 8 and said ends are preferably equipped with rollers 11 to travel 85 onto said supports when the frame is swung to one position or the other. Suitable means 12 are provided for locking the frame 8 against movement when it is properly set.

Not only is the car 1 mounted on the 95 frame 8, but its shock absorber 4 is likewise carried thereby, and although said shock absorber might vary in form, it preferably consists of a fixed cylinder 13, a piston 14, a piston rod 15 connecting the piston with 100 the car 1, and any suitable valve or connection 16 for permitting slow escape of air from the cylinder, this arrangement being illustrated most clearly in Fig. 11. It will thus be seen that when the car 1 is rapidly 105 moved by depositing of the mail sack S therein, it must move against the resistance caused by the expulsion of air from the cylinder 13 by the piston 14, and this serves to gradually bring the car to a standstill. 110

To prevent any possibility of the car 1 being thrown from its tracks 3, I may provide a roller 17 carried by said car and traveling along the under side of an additional track 18 carried by the frame 8. The roller 17 may well be mounted on the lower end of a hanger 19 depending from the piston rod 15 and clamped against an arm 20 which extends downwardly from the bottom of the car 1. Although this construction might be followed, others could be used to equal advantage.

The traveling unit T is illustrated most clearly in Figs. 2 to 10, said unit including 15 a guide 21 hingedly mounted at 22 on one side of the mail car, for swinging against the side of the latter as seen in dotted lines in Fig. 3 or for disposition at right angles to the track as seen in full lines. Suitable 20 hooks 23 and 24 or other preferred means may be employed for holding the guide in either of its positions. The upper edge of the guide 21 is provided with a roller 25 located at the inner end of said guide, while 25 another roller 25' is mounted in the lower portion of said guide, at its outer end. A horizontal slide bar or arm 26 is slidable in the guide 21 and has its inner end 27 offset downwardly from its outer end, said outer 30 end resting on the roller 25', while said end 27 extends under the roller 25. The outer end of the arm 26 carries the mechanism for holding the mail sack and consequently there is a downward strain on the outer end 35 of the bar and an upward strain on the inner end thereof, but these strains are received by the rollers 24 and 25 and thus the bar may be slid in or out with ease. A handle or the like 28 may be provided for this purpose if 40 desired.

The outer end of arm 26 carries a reversible, horizontally swinging head 29 which might be connected thereto in any adequate manner, although intermeshing knuckles 30 45 and a pivot pin 31 are preferably employed for this purpose. The head 29 may be of any suitable shape, but in most instances I prefer to construct the same in the form of an inverted L with the knuckles 30 on the 50 vertical arm thereof, while the horizontal arm 32 serves to support the sack S.

Any suitable means may be employed to hold the head 29 in either one position or the other, according to the direction in which 55 the train is traveling, but I prefer to provide the outer end of arm 26 with a fixed disk 33 having openings 34 through which a pin 35 is insertible, said pin being slidably carried by the head 29, for instance, in a 60 lug 36 at the lower end of said head.

By any suitable connection, I attach the mail sack S to a ring 37 and pass such ring over the horizontal arm 32 of the head 29, and I employ a novel latch mechanism for 65 holding the ring in place on the arm until

the sack is deposited in the car 1, and for then releasing said ring to permit the arm 32 to withdraw therefrom. In the present showing, I have illustrated a vertical lever 38 fulcrumed in a slot 39 in the arm 32 and 70 provided with a downturned end 40 to extend over the ring 37, said end being normally held in a socket 41 in the arm 32 by means of a coiled spring or the like 42 which normally holds the lever 38 in position to hold the ring 37 against removal. The lower end of lever 38 forms a trip to strike the upper end of the bumper 5 or a release plate 43 carried by the car 1, and 75 it will be seen that this lever is in front of 80 the sack S. Thus, by the time the lever is released by contact with the receiving car, the sack has been deposited in said car against the bumper 5, which starts the car along its tracks 3.

After its use, the slide bar 26 may be drawn into the car, and I may provide spring detents 44 and a lug 45, carried respectively by the guide 21 and bar 26, for yieldably holding said bar in either projected or retracted position. The shape of the lug 45 and its manner of co-action with the detents 44, is illustrated most clearly in Figs. 1 and 5, said detents being adapted to snap into a central depression with 95 which said lug is provided.

In operation, the sack S is hung by the ring 37 upon the head 29 and held by the lever 38, said head being swung to the proper position, according to the direction 100 in which the train is traveling. The slide bar 26 is then projected, after first swinging the guide 21 outwardly from the wall of the car and anchoring it by means of the hook 23. In the meantime, the car 1 105 has been positioned at the ends of the tracks 3 to receive the sack S, and when said car is reached, said sack and the lever 38 strike the same at approximately the same time. The lever 38 is thus released to allow the 110 head 29 to withdraw from the ring 37, leaving the sack or sacks of mail in the car 1. The shock of receiving the mail is decreased to a large extent by the bumper 5, but nevertheless the car 1 is caused to travel along 115 the tracks 3. However, the shock absorber 4 slowly brings the car to a standstill so that the sacks may be removed, after which said car is returned to the receiving end of the tracks. After delivery of the mail, the 120 arm 26 is of course drawn into the train and its guide 21 is then folded against the wall of the coach as indicated in dotted lines in Fig. 3. By swinging the frame 8 and the head 29 to one position or the other, the 125 device may be used regardless of the direction in which the train is traveling.

From the foregoing, taken in connection with the accompanying drawings, it will be seen that although my invention is of 130

comparatively simple nature, it will be highly efficient and in every way desirable, and since probably the best results are obtainable from the details disclosed, they may 5 well be followed. I wish it understood, however, that within the scope of the invention as claimed, considerable latitude is allowed for making numerous minor changes.

I claim:

- 10 1. In a railway mail delivery apparatus, a mail bag receiver open at its top and at one end, said receiver being disposed at one side of a railway, an arm extending laterally from a railway car and having a rearwardly directed portion at its outer end parallel with the railway and adapted for loose reception in a mail bag supporting ring, and a latch for holding the ring on said arm, said latch having a rearwardly 15 movable releasing arm in front of its ring engaging portion to strike said receiver and release the latch, thereby permitting said rearwardly directed end of said arm to withdraw forwardly from the bag supporting 20 ring.
- 25 2. In a railway mail delivery apparatus, a track at one side of the railway, a receiving car movable along said track, means carried by a railway car for holding a mail sack in position for reception in said receiving car, a releasing trip device for said holding means, and a bumper in said receiving car adapted to be struck by said trip device and by the mail sack.

3. In a railway mail delivery apparatus, 35 a track at one side of the railway, a receiving car movable on said track, an arm extending laterally from a railway car, a reversible head on the outer end of said arm, means on said head to hold the mail sack 40 in position for reception in said receiving car, and means for releasing said holding means when the sack is deposited in said receiving car; said receiving car, in addition to said head, being reversible to permit the 45 apparatus to operate regardless of the direction in which the railway car is traveling.

4. A mail bag receiving unit for railway mail delivery apparatus, comprising a track 50 at one side of the railway, a receiving car movable along said track, a piston rod secured to said car and having a piston, and an elongated cylinder in which said piston operates, means being provided to permit slow escape of air from said cylinder. 55

5. A structure as specified in claim 4 together with a horizontal frame on which said track and said cylinder are mounted, means pivotally mounting the center of said frame to permit horizontal swinging thereof to reverse the position of the car, fixed supports upon which the ends of said frame rest when in either position, and means for locking said frame normally against turning. 60

In testimony whereof I have hereunto set my hand.

OTTO M. GILBERTSON
